(57) **CLAIM**

The ornamental design for an under-carriage for a playseat, as
shown and described.

DESCRIPTION

FIG. 1 is a left perspective view of the under-carriage for a
playseat;

FIG. 2 is a right perspective view of the under-carriage for a
playseat;

FIG. 3 is a right side elevational view of the under-carriage for
a playseat;

FIG. 4 is a left side elevational view of the under-carriage for
a playseat;

FIG. 5 is a bottom perspective view of the under-carriage for
a playseat; and,

FIG. 6 is a top perspective view of the under-carriage for a
playseat.

The broken lines in the drawings are included for the purpose
of illustrating environmental structure and form no part of the
claimed design.
